Primary Examiner — Karen S Acker(74) *Attorney, Agent, or Firm* — Alan D. Kamrath;
Kamrath IP Lawfirm, P.A.(57) **CLAIM**

I claim the ornamental design for a woven cloth, as shown and described.

DESCRIPTION

FIG. 1 is a perspective view of woven cloth showing my new design;

FIG. 2 is a front elevational view thereof, the rear being a mirror image;

FIG. 3 is a right side view thereof, the left being a mirror image; and,

FIG. 4 is an enlarged detail view of a portion of the woven cloth as shown in FIG. 1.

The evenly spaced broken lines illustrate portions of the woven cloth that form no part of the claimed design.

The dot dash dot broken lines in FIGS. 1 and 2 depict the left and right side boundaries of the claim and form no part thereof. The dot dash dot broken line perimeter in FIG. 4 defines the boundary of the detail area and forms no part of the claimed design.
